[57] CLAIM

The ornamental design for a trigger-actuated glue gun, as shown and described.

DESCRIPTION

FIG. 1 is a top, front and right side perspective view of a trigger-actuated glue gun showing our new design;

FIG. 2 is a top plan view thereof;

FIG. 3 is a right side elevational view thereof, the left side is a mirror image thereof;

FIG. 4 is a bottom plan view thereof;

FIG. 5 is a front elevational view thereof; and

FIG. 6 is a rear elevational view thereof;

The broken line showing of a power cord fragment in FIGS. 1, 3, 5 and 6 is for illustrative purposes only and forms no part of the claimed design.

FIG.1

FIG.2
